UNITED STATES PATENT OFFICE.

WILLIAM M. CUMMER, OF CLEVELAND, OHIO.

CYLINDER FOR MECHANICAL DRIERS.

No. 856,770.

Specification of Letters Patent.

Patented June 11, 1907.

Application filed January 18, 1907. Serial No. 352,858.

To all whom it may concern:

Be it known that I, WILLIAM M. CUMMER, a citizen of the United States, residing at Cleveland, in the county of Cuyahoga and State of Ohio, have invented certain new and useful Improvements in Cylinders for Mechanical Driers; and I do declare that the following is a full, clear, and exact description of the invention, which will enable others skilled in the art to which it appertains to make and use the same.

My invention relates to cylinders for mechanical driers, and the invention consists in a cylinder constructed of a plurality of sections running the full length thereof and provided with draft inlets for air and the products of combustion extending the full length of the cylinder between said sections, the said sections being curved to the segment of a circle in cross-section and spaced apart along their overlapping edges and provided with guards inside over said draft inlets to prevent material from working out of the cylinder and to provide a draft chamber, all substantially as shown and described and particularly pointed out in the claims.

In the accompanying drawings Figure 1 is a longitudinal sectional elevation of a drier containing my invention and Fig. 2 is a cross section thereof.

The invention herein resides more particularly in drying cylinder C as a new and practical article of manufacture and sale, the other parts shown being old in the main. The said cylinder is constructed in several sections longitudinally, three in this instance, 2, 3 and 4, respectively, running the full length of the cylinder and constituting the entire body thereof. The said sections themselves may be constituted in one piece their full length, or of several pieces riveted together, and all are curved to the same cross section and arranged to meet along their edges lengthwise, except that each section comes opposite another at one edge and is spaced apart from the next section at its other edge, and the several sections rigidly united and constituted into a complete cylinder by means of longitudinal bars or spacing pieces B. The said pieces or bars are located between the said sections outside the containing portion of the cylinder and between adjacent edges thereof, substantially as shown. That is the said strips or pieces occupy a space between the inner edge of one section and the outer edge of the other section at that point, and said edges or edge portions of sections are spaced apart by said pieces sufficiently to provide free admission of air and products of combustion from furnace F. Furthermore, it will be observed that the said connecting bars or pieces B have the shape, preferably, of Z beams in cross section, and are firmly riveted to both sections so as to give perfect rigidity and strength to the cylinder. Said bars or pieces also are provided with draft holes or openings 2 through the web thereof, as above indicated, and the said bars and series of openings therein run lengthwise of the cylinder. But this in itself would not be sufficient to make a cylinder of this style operative or practical for drying purposes because the drying material is tossed and tumbled about in the cylinder in such manner, and is of such subtle quality usually, that there would be excessive waste and loss through the draft openings. Hence the need of auxiliary means to confine the material as well as to maintain a free circulation through the cylinder of the drying medium. To these ends, therefore, the said openings are guarded and the material confined in the cylinder so far as said openings are concerned by means of two parallel walls G and H, respectively forming an inside draft chamber. The said walls have the form of plates, and plate G is the guard-plate proper, and is bent to L shape or right angles in cross section and secured along its base to the outer cylinder section back from the entrance thereto through openings 5 a distance relatively as shown, so that its right angled overhanging portion or cover 6 overlaps the said chamber and shields the same from any direct fall of the material from above. Wall plate H stands inward from plate G and is attached along the edge of the inner cylinder section and is sufficiently lower than plate or wall H to leave a draft space over the same beneath the cover 6 of plate G, said overhanging portion extending inward beyond plate H far enough to prevent material dropping from above behind the same when the said parts are turned some distance past the bottom of the cylinder. Further around in the direction of rotation as indicated by the arrows, this exact protection does not obtain, but then the longitudinal draft

channels are not in position which exposes them unduly to the falling material, and I intend that a percentage of the material shall drop thereon so as to promote the drying of the same. This may be done without materially affecting the inflow of air because of the peculiar construction and operative relations of the several draft chambers within or behind plates G and H, and any material that works into said draft chambers must inevitably fall back into the body of the cylinder when rotated around far enough to make such discharge certain. But in no case can any of the material escape from said sheltered draft chamber through inlet passages 5, and any exposure of material occurring on or about the walls of the draft chambers will only promote its drying and operate to the advantage of the system.

20 The guard plates G and H are disposed in the cylinder in such positions relatively that they take the place and do the service of lift blades L, of which three are shown intermediate.

25 Among the advantages of this construction of cylinder over others familiar to me are, first, the taking in of the drying medium into the cylinder relatively near to the side thereof, where it necessarily is drawn through the material as the material is tossed or cascaded in the cylinder. This could not occur to any such advantageous degree if the heating medium or agent were delivered at or near the center of the cylinder where at any rate the suction from the blower at the front of the cylinder is most active, and to which the air naturally works. It will be seen that the undried material about the side of the cylinder back of such approximately central inlets would get no practical benefit from the inflowing air, but by establishing the inlets near the surface of the cylinder all around the exposure of the material to the drying agent is greatly increased and the machine is thus rendered that much more efficient without increasing the heat units. Furthermore, this construction does away with all obstructions to the working of the material toward the discharge end of the cylinder, which is necessary to maintain at a rate of speed determined upon when the cylinder is set, and the entire interior of the cylinder is clear except for the air shaft chambers which, being lengthwise do not impede the flow of the material.

What I claim is:

1. A drying cylinder formed of a plurality of segmental sections spaced apart at their edges, and rigid connecting pieces extending

the full length of the cylinder between the edges of said sections and provided with draft openings.

2. A cylinder for a drying apparatus consisting of a plurality of sections extending from end to end thereof, spacing pieces running lengthwise of the edges between said sections and rigidly uniting said sections and provided with inlet openings for the drying medium, and longitudinal draft chambers for said openings within the cylinder.

3. A drying cylinder in sections the full length thereof segmentally curved in cross section, said sections separated along both edges, spacing pieces between the said edges provided with draft openings, and a covered draft chamber lengthwise next within said openings provided with side and top guard portions.

4. A drying chamber having longitudinal openings at intervals about its periphery extending from end to end thereof, rigid connecting pieces located in said openings and provided with draft holes, and draft chambers located within said cylinder into which said draft holes discharge provided with parallel walls of different elevation and the higher of said walls having a right angled portion extending across the edge of the lower wall and apart therefrom.

5. A drying cylinder consisting of several longitudinal segmental sections having their meeting edges spaced apart and a walled draft chamber projecting inward the full length of said cylinder at the intersection of said sections and having a side opening parallelly arranged to the axis of the cylinder.

6. A drying cylinder formed in segmental sections lengthwise and having draft openings between the meeting edges of said sections, and walled draft chambers over said openings constructed to lift the material being dried and adapted to prevent the escape of material through said draft openings.

7. A drying cylinder having longitudinal draft openings, and a draft chamber inside said cylinder having parallel walls on opposite sides of said openings and an inner wall to cover said draft openings and a draft inlet along one side wall, and said walls adapted to lift the drying material and confine the same within the cylinder.

In testimony whereof I sign this specification in the presence of two witnesses,

WILLIAM M. CUMMER.
